UNITED STATES PATENT OFFICE.

OSKAR FINKHAUS, OF WURZBURG, GERMANY, ASSIGNOR TO BOHN & HERBER, MASCHINENFABRIK UND EISENGIESEREI, OF WURZBURG, GERMANY, A KOMMAGITGESELLSCHAFT OF GERMAN LAW.

GRIPPER MECHANISM OF PRINTING PRESSES.

Application filed August 2, 1924. Serial No. 729,813.

To all whom it may concern:

Be it known that I, OSKAR FINKHAUS, a citizen of Deutsches Reich, and residing at 34 Petrinistreet, Wurzburg, Bavaria, Germany, have invented certain new and useful Improvements in and Relating to the Gripper Mechanism of Printing Presses; and I do hereby declare that the following is a full, clear, and exact description of the same.

10 In printing presses with a continuously rotating printing cylinder it frequently happens that several sheets to be printed, laid to the same laying on gages are irregularly seized by the gripper mechanism and 15 therefore do not show an accurate register. This is undesirable even if there are only slight deviations for multi-colour printing work and unfavourably affects the quality of the finished product. The invention 20 has for its object to eliminate the drawback in question by modifying the arrangement of the support for the sheets to be printed, whilst using without any other modification the well known gripper mechanism of such machines which has proved 25 so satisfactory and in which several grippers are mounted on a spindle mounted directly in the printing cylinder and seize the sheet in co-operation with a radially and 30 tangentially movable sheet support mounted between stops in the printing cylinder. The invention aims moreover at providing a simple and durable gripper device, easy to manipulate.

35 The invention consists in the combination of grippers mounted on a gripper spindle mounted directly in the printing cylinder, a sheet support mounted in the printing cylinder in a radially and tangentially adjustable manner and rotating 40 with the printing cylinder, means for rotating the gripper spindle, and means for stopping the sheet support opposite a fixed point of the machine frame when the grippers close down on the said support, and for 45 releasing it again immediately afterwards.

The invention comprises moreover other details hereinafter more particularly described.

50 Two constructions according to the invention are illustrated by way of example in the accompanying drawings in which the

same reference numerals indicate the same parts.

In the said drawings:

55 Figures 1 and 2 are respectively a cross-section and a plan of a gripper device.

Figure 3 is a section, on an enlarged scale, of the same device, in the position immediately before the grippers close down.

60 Figure 4 is a similar section in the position immediately afterwards.

Figure 5 is a section through an alternative construction of the gripper device according to the invention, in the position immediately before the closing down of the grippers. Figure 6 a corresponding plan.

65 Figure 7 is a section corresponding to Figure 5 in the position immediately after the closing down of the grippers.

70 Figure 8 a similar section in the position for putting on the cylinder blanket.

75 In the continuously rotating cylinder 1 of a printing press (Figures 1-4 of the drawing) is rotatably mounted the gripper spindle 2; it carries a number of grippers 3 firmly secured to it, which are distributed throughout the whole length of the cylinder, and outside the cylinder, a gripper shoe 4 which is also firmly keyed to it. The gripper shoe co-operates with a cylindrical stop 6 secured to the frame 5 of the machine, so that in passing the stop 6 the gripper spindle is rotated. During this rotation the gripper shoe moves between the stops 7 and 8 which are provided outside on the end wall or cover of the printing cylinder. To the gripper spindle are also keyed, on the inside of the cylinder cover cranks 9 which are pressed upwards by means of pivoted rods 10 and pressure springs 11 mounted on the said rods. All these parts are already known for the same purpose and in the same arrangement in printing presses. Adjacent to the gripper spindle in the cylinder is 85 mounted the sheet support 12 which is constituted by a rail or bar extending in the longitudinal direction of the cylinder. To the sheet support is secured adjacent to each end of the same a bolt 13 which can slide in rings 14; the rings 14 are mounted so as to be freely rotatable by means of pins 15 on the inside of the cylinder cover. Between the rings 14 and the sheet support are in-

55

100

serted pressure springs 16 which press the sheet support away from the centre of the cylinder. The springs 16 are weaker than the springs 11, so that the sheet support can be forced to a certain extent by the springs 11 into the cylinder when the grippers 3 close down on its upper edge.

Moreover on the sheet support adjacent to its ends are mounted arms 17 with which 10 engage tension springs 18, the opposite ends of which are secured to holders 19 screwed into the cover of the printing cylinder. With the arms 17 co-operate cam discs 20 keyed to the gripper spindle 2 and each of 15 which is provided with a projection or boss 21. As long as the cylindrical surfaces of the cam discs 20 engage with the arms 17, they allow the sheet support to project slightly beyond the circumference of the 20 printing cylinder 1 but when the bosses 21 come into contact with the arms 17 the sheet support will be forced into the cylinder.

At the ends of the sheet support are provided stops 22 which engage with adjustable stops 23 secured to the inside of the cylinder cover. At the front edge of the laying-on board or table 24 are provided elastic prongs or tongues 25 on which the 30 sheet 26 to be printed can be laid to the fixed laying-on gages 27. Moreover at both sides of the laying-on table on the machine frame are arranged fixed and adjustable stops 28 which co-operate with the stops 22 35 of the sheet support. The stops 28 are bent into a right angle, the longer branch of which is situated in the plane of the laying-on table, and the shorter branch projects downwards near the laying-on gages 27.

40 The shape of the gripper shoe 4 is such that the points of the grippers 3 come down on the sheet vertically consequent upon the rotation of the cylinder.

Shortly before the device reaches the 45 position shown in Figures 1 and 3, the gripper shoe 4 has engaged with the stop 6 whereby the gripper shoe is rotated and moved away from the stop 8. At the same time the spindle 2 has been rotated and with 50 it the cam disc 20. The arms 17 have disengaged from the projection 21 of the cam discs 20 and engaged with the cylindrical surfaces of the cam discs.

At the same time the sheet support 12 has 55 been pushed out of the printing cylinder by the springs 16, to such an extent that its stops 22 engage with the horizontal portion of the stops 28, and its upper edge engages with the tongues 25 and the sheet 26. The 60 printing cylinder continues to rotate in contact with the printing sheet and the tongues 25. In the position shewn in Figures 1 and 3, the stops 22 engage with the vertical portion of the stops 28. Immediately afterwards the grippers 3 close down on the

printing sheet 26 and therefore press at the same time against the sheet support 12.

Owing to the greater strength of the springs 11 the sheet support 12 will be forced into the printing cylinder, the springs 70 16 being compressed at the same time, and the gripper shoe 4 meanwhile disengaging

from the stop 6, in this way the sheet support is finally disengaged from the stops 28, Figure 4; from the moment of the meeting of the stops 22 with the vertical portion of the stops 28 to the moment of the release, 75

the sheet support 12 cannot participate in the rotation of the printing cylinder, but remains stationary. During this period, 80 owing to the continued rotation of the cylinder, the gripper points move at right angles to the sheet 26 to be printed as indicated by the arrow in Fig. 5, that is to say said gripper points also do not participate geometrically in the rotation of the printing cylinder.

85 The gripper points move relatively to the sheet 26 in a curve somewhat like the curved dotted line indicated on Fig. 3, and said curve has some elements perpendicular to the sheet support. By properly shaping the gripper shoe 4 as indicated in Figs. 3 and 4, the grippers in closing down move perpendicularly or normally to the printing sheet 26.

90 The sheet support 12 remaining stationary and the gripper points moving perpendicularly to the sheet and to the upper surface of the sheet support, the gripping is effected in the same manner as it would be by a stationary gripper on a stationary table. Only on the sheet support 12 being released by the stops 28 will it continue to move with the printing cylinder and the grippers 3 and at that moment the printing sheet 26 will be moved by the gripper device 95 and remain in a fixed position relatively to the latter.

100 The printing sheet will now travel with the printing cylinder and will be printed upon and released again when the gripper shoe 4 is again turned into its initial position. On the grippers beginning to turn again the sheet support is also released and returns to its normal position relatively to the stops 28.

110 The construction shown in Figures 5-8 of the drawing, differs from the first construction chiefly by the fact that the active part of the sheet support is made adjustable in a radial and tangential direction of the printing cylinder by mounting it so that it can turn about the gripper spindle, for the reason that the active part of the sheet support is the supporting or outer surface, and said active part as well as the whole support, is moved on the arc of a circle about the gripper spindle 2. This arc is active only 115 on its part near the circumference of the cylinder 1, and said arc of the circle obviously elongates in a direction either radial or 120

125

130

tangential with respect to the cylinder, and when the gripper points close down on the printing sheet, the outer surface of the sheet support is prevented from rotating with the 5 circumference of the cylinder, that is to say, its tangential movement with respect to the cylinder is what is employed by the present invention. During the next phase of operation, the grippers move the sheet support to 10 ward the center of the cylinder, which is the radial movement employed in the present invention. Other movements of the sheet support at the same time are negligible, and do not effect the operations herein described.

15 The construction and the arrangement of the printing cylinder 1, gripper spindle 2, grippers 3, gripper shoe 4, cranks 9, laying-on table 24, tongues 25, laying-on gages 27, stops 28 and of the corresponding parts, are 20 substantially the same as in the construction shown in Figures 1-4. The sheet support 29 is however mounted on the gripper spindle in a freely rotatable manner by means of two brackets 30 secured to its ends.

25 On the sheet support are mounted, adjacent to its ends, fingers 31 which engage with the ends of spring blades 32, the other ends of which are secured to the printing cylinder 1. The cranks 9 are provided with 30 cams 33 which depress the spring blades 32 in the initial position of the gripper spindle 2. At the end of the sheet support are provided stops 38. On a spindle 34 arranged parallel to the gripper spindle, are mounted 35 a number of brackets 35 which carry buffers 36 forced outwards by springs 37. The buffers 36 engage from the inside against the sheet support and press it outwards. The spindle 34, in addition to the brackets 35, 40 carries also S-shaped springs 39 intended to secure the cylinder blanket 40. The spindle 34 can be rotated by means of a hand lever 41 which is bifurcated at the end and secured outside to the end wall of the printing cylinder. At the same place is pivoted a 45 clamp 42 which can be turned into the gap between the bifurcated ends of the lever 41 and secured there by screwing down a handle 43.

50 The operation of the device is as follows:—

The gripper spindle together with the shoe, grippers, cams 33 and spring blades 32 are first in the position shown in Figure 58. The tail of the gripper shoe engages with the stop 8. The other parts in the cylinder being in position indicated in Fig. 7, the sheet support 29 is pressed outwards by the buffers 36 until the fingers 31 engage with the spring blades 32; the outer edge of the sheet support is during that period still in the interior of the printing cylinder. During the rotation of the printing cylinder before the position shewn in Figure 5 is reached, the gripper shoe 4 will

strike the cylindrical stop 6 secured to the frame and will thus be turned say to an angle of 135°. The cams 33 of the cranks 9, previously depressing the spring blades 32, will be brought into the position shown 70 in Figure 5 so that the sheet support 29 will be moved by the buffers 36 outwards beyond the casing of the printing cylinder. During the rotation of the printing cylinder, the sheet support will travel for a short 75 distance along the tongues 25; finally its stops 38 will strike, in the position shewn in Figure 5, the vertical portions of the stops 28. At that moment the upper edge 80 of the sheet support will be therefore prevented from continuing its rotation about the axis of rotation of the printing cylinder.

Almost simultaneously, the grippers 3 will close down on the printing sheet 26 and the sheet support 29, the said grippers 85 moving then at right angles to the sheet. As the printing cylinder continues to rotate without an interruption, the sheet support 29 will slide off from the stops 28, its upper edge moving in respect to the frame 90 of the machine in the radial direction of the cylinder. The movement is facilitated by the arrangement of the gripper spindle 2, about which the sheet support 29 turns, obliquely below the edge of the stop 28. The centre of rotation of the movement of the sheet support relatively to the frame of the machine is situated in the point of intersection of the radius of the printing cylinder, drawn through the centre of the gripper spindle 2, with a line drawn through its lower corner point at right angles to the vertical arm of the stop 28.

95 The movement of the sheet support is independent of the movement of the gripper shoe 4. The forces of acceleration produced are taken up, on the one hand, by the stops 28, and on the other hand, by the bearings of the gripper spindle 2 in the printing cylinder. The gripper shoe 4 is 100 given such a shape that the grippers 3 follow the movement of the sheet support in the same time ratio.

105 From the moment of striking the vertical edge of the stops 28 to the moment of its release therefrom, the position shown in Figure 3, the upper edge of the sheet support 29 executes only a movement in the radial direction of the cylinder. Consequently during that interval the printing sheet is seized in the same manner as by stationary grippers on a stationary support. Only after the sheet support has been released from the stops 28, will it 115 travel again with the printing cylinder, being held between the grippers 3 and the buffers 36. At the moment of the release of the sheet support by the stops 28, the printing sheet which up to that moment was 120 at rest, will be carried by the printing cylinder 125 130

inder without being able to move relatively to the cylinder; it will be then printed upon and when the gripper shoe 4 returns to its initial position again released.

5 The cylinder blanket 40 is put on in the following manner:—

The handle 41 is released and turned in the anti-clockwise direction, Figure 8. The buffers 36 will then also be turned downwards. The sheet support 29 will follow them and finally the springs 39 will be released and pass into the space just left free by the sheet support; the end of the cylinder blanket can then be conveniently put on. If 15 the handle 41 and with it the rod 34 are then turned back in the clockwise direction, the springs 39 will first engage with the cylinder blanket, then they will be cocked, whilst at the same time the buffers 36 and 20 with them the sheet support 29 will be raised again. The handle 41 will then be locked again by means of the clamp 42 operated by the handle 43.

The invention described offers the following advantages:—

In spite of the movement of the cylinder, the printing sheet is seized as accurately as by stationary grippers and a stationary sheet support; it can therefore engage with 30 fixed laying-on gages and will not move at the moment of seizing. Each sheet will be therefore locked on the cylinder in the same position as the others. During the rotation of the printing cylinder, the edge 35 of the printing sheet will not slide on the casing of the printing cylinder and therefore will not be damaged. The whole device is extremely simple and utilizes the well known gripper device which has proved 40 so satisfactory in such machines. The second construction has this advantage over the first one, that the sheet support will be driven direct by the gripper spindle 2 during the renewed acceleration after striking 45 the stops 28, so that the grippers 3, the gripper shoe 4 and the stop 6 are relieved from the forces which these parts have to resist in the first construction for the acceleration of the sheet support.

50 Having now particularly described and ascertained the nature of my said invention and in what manner the same is to be performed I declare that what I claim is:—

1. In a printing press comprising a frame, 55 a rotary printing cylinder supported in said frame, a gripper spindle rotatably supported within and rotating with said printing cylinder, grippers mounted on said gripper spindle, a printing sheet support mounted within and rotating with said printing cylinder, a fixed stop outside of and adjacent to said printing cylinder, means on said spindle for engaging said fixed stop and actuating said gripper spin-

65 dle, and means cooperating with said printing sheet support for momentarily stopping said support in a determinate position and relation with respect to an adjacent point on the frame when the grippers close down on said sheet support and releasing said support immediately after said stopping.

2. In a printing press such as set forth in claim 1, in which the printing sheet support is adjustable oblique with respect to the outer cylindrical surface of the printing 75 cylinder.

3. In a printing press such as set forth in claim 1, in which said printing sheet support rotates with said cylinder until it engages said stopping means.

4. In a printing press such as set forth in claim 1, in which the means on the spindle engaging the fixed stop is a cam surface of such configuration or curvature as to actuate the grippers on the spindle in such a manner that the engaging ends of said grippers close down on the printing sheet support 85 perpendicularly or normally to the printing sheet.

5. In a printing press such as set forth 90 in claim 1, in which is provided means for actuating the printing sheet support so that said support is moved out of the printing cylinder before its engagement with the stopping means.

6. In a printing press such as set forth in claim 1, in which the means on the spindle engaging the fixed stop is a cam surface of such configuration or curvature as to depress the sheet support back into the 100 printing cylinder after said grippers have reached said sheet support.

7. In a printing press such as set forth in claim 1, in which the printing sheet support is pivoted and rotatable on the gripper 105 spindle.

8. In a printing press such as set forth in claim 1, in which the printing sheet support is pivoted and rotatable on the gripper spindle, a cam on the gripper spindle, said 110 cam engaging said sheet support in such a manner as to allow said support to swing outwards from the printing cylinder during the advance of the grippers but hold said support back in the cylinder at and after 115 the release of the sheet by the gripper.

9. In a printing press comprising the construction set forth in claim 1, and buffers which cooperate with the printing sheet support to press the same outwards from the 120 cylinder, a cylinder blanket, an oscillatory rod mounted longitudinally within the printing cylinder, means for locking said rod against oscillation, and S-shaped springs carried by said oscillatory rod and constructed and arranged for engaging and securing said blanket to said cylinder.

OSKAR FINKHAUS.
